BOTTLE CAPPING MACHINE

Charles S. Price, Rutherford, N. J.

Application April 3, 1952, Serial No. 280,286

10 Claims. (Cl. 226—85)

1

This invention relates to bottle-capping machines and, more particularly, to one improved to crimp caps on bottles under high pressure without danger of rupturing the deformable crimping element.

The principal object of my invention, generally considered, is to provide improved and reliable means whereby the deformable crimping element or cup and the receiving foiling head may be automatically or manually moved to operative position prior to a controlled safe distortion of the element and said element then allowed to return to normal shape by the release of the deforming force before moving the crimping head away from operative position.

Another object of my invention is to provide crimping mechanism which will operate without injuring the deformable capsule or foiling head.

A further object of my invention is to provide mechanism which will operate automatically or as desired by the operator.

Other objects and advantages of the invention will become apparent as the description proceeds.

Referring to the drawing, in which like parts are designated by like reference characters,

Figure 1 is a vertical sectional view of apparatus embodying my invention.

Figure 2 is a vertical sectional view corresponding to Fig. 1, but showing a modification.

Figures 3, 4 and 5 are diagrammatic views illustrating alternative forms of control mechanism.

Either form of machine shown in the drawing can be used with a machine which applies caps or capsules 11 to the heads of bottles 12, or said caps can be applied to the bottles by hand. Said caps 11 are desirably made of metal foil, but can be made of other suitable yieldable material.

To do a satisfactory job of crimping metal caps on bottle heads, an excess of 200 pounds per square inch is required. We have to provide this pressure without danger and without the risk of rupturing the flexible or rubber cup comprising the foiling head, in case the bottle is not in place to have a cap crimped over its head and neck.

Others have attempted to so crimp by using high pressure air instead of liquid. The result has been that when there is a "miss," the bottle not being in place when the pressure is applied, this high pressure air ruptures the rubber cup.

My crimper does two things which are essential for a successful operation. First, it sup-

plies an exactly-controlled hydraulic pressure automatically applied and, second, it limits the total amount of compression to a point beyond that required to develop this pressure against the bottle neck and still not enough to overstress the rubber cup in case a bottle is not in place when the pressure is applied.

Essentially, this device consists of an air cylinder directly connected to and in tandem with an hydraulic cylinder, in such a manner that the pressure in the hydraulic cylinder is increased, as compared to that of the air, resulting in a final effective pressure approximately equal to the air pressure multiplied by the ratio of the areas of the air cylinder and the hydraulic cylinder. A preferred ratio in my device is about 5½ to 1, that is a piston in a 3½" diameter air cylinder actuating a piston in a 1½" diameter hydraulic cylinder. This means that 40 pounds of air pressure is boosted to about 220 pounds of hydraulic pressure. The stroke of the piston in the hydraulic cylinder is in the present embodiment limited to 2 inches, as this has been found to be the optimum stroke to insure complete crimping and not enough to cause cup damage when a bottle is not in place during the crimping operation.

In the machine of the embodiment of Figure 1, I use a piston with a six inch stroke in the air cylinder. Such a piston has the multiple purpose of lowering, crimping, and raising the crimping head from the bottle after the crimping operation is completed. In other words, of this total 6 inch stroke, 4 inches may be used to raise and lower the crimping head over the neck of the bottle, and the remaining 2 inches may be used to compress the liquid around the rubber crimping cup, which movement has been found sufficient for the purpose and will not effect rupture of said cup even if a bottle is not in place. However, these distances may be varied with the size of the bottle cap to be applied.

Referring now in detail to the embodiment of my invention illustrated in Figure 1, air cylinder 13 is fitted with a double-acting piston 14, the piston rod 15 of which passes through gland 58 in the lower head 24 and is directly connected to, or continued as the piston rod 16 which actuates the piston 17 in the hydraulic cylinder 18. The cylinder 13, which may consist of a thin-walled intermediate hollow steel cylindrical portion closed at its ends by ported upper and lower heads 24 and 24', may be fixedly mounted on a suitable support 30, as illustrated, at the required distance above the bench or other means 40 upon

which stand the bottles 12. The cylinder 13 may be held at the proper height after adjustment by tightening the set screw 50.

The cylinder 18 is part of a crimping member or head generally designated 19, comprising a cross-head 21, which may be connected to or form part of the cylinder 18. The cross-head 21 is suitably mounted on guide rods 22, depending from the cylinder 13, and terminating in stops 20, which may be nuts threaded on said rods, for limiting movement of the cylinder 18 from the cylinder 13. The cylinder 18 is biased toward lowermost position by the action of coil compression springs 23 mounted on said rods 22 and acting between the lower head 24' of the cylinder 13 and the cross-head 21. The lower end of the cylinder 18 is normally closed by the crimping cup or foiling head 25, of proper size to normally freely receive the head and neck of the bottle 12 to which a cup 11 is to be crimped. The cup 25 is made of rubber or other suitable resilient and deformable material, and held in place by a nut 26.

The liquid 27 (usually water), in the cylinder 18 and between the cup 25 and the piston 17, is normally at the level 28 in an expansion chamber 29 on the top of the cross-head 21. As the hydraulic piston 17 rises and falls, the water above the piston rises and falls in the expansion chamber, passing in and out of ports 31 in plug 32. There is a special "bleed" port 33, which opens below the piston in its upper position, connecting the cylinder below the piston with the expansion chamber 29. This connection is only established at the top, non-compression, or up stroke of the hydraulic piston and then any trapped air passes freely through the "bleed" port and out of the hydraulic cylinder. This is important, as any air trapped in the hydraulic cylinder causes improper action on crimping. In other words, the hydraulic system is automatically "bled" between each compression stroke.

It is further necessary to provide means for the liquid 27 to rise and fall in the expansion chamber 29, without appreciable loss. To accomplish this I provide a cover 34 having a gland 35 through which the rod 15 reciprocates, and internal baffles 36 and 37 so that the air from the expansion chamber as liquid rises therein, is forced through staggered apertures 38 forming a devious path, as indicated, before being permitted to escape. Along this devious path, the air gives up liquid with which it may have co-mingled, and the air itself passes in and out of a port in the cover 34.

In operation, the piston 14 is normally at the top of the stroke. A bottle 12 with a cap 11 loosely fitted over its head and neck, having been placed beneath the crimpler, air automatically or by operator is introduced above piston 14, forcing it downward until the crimping head 19 is at the lower end of the guide rods 22 and bottomed against guide rod stops 20. At this point, the descent of the crimping head 19 is arrested, and the balance of the stroke of the air piston 14 is used in lowering the hydraulic piston 17 in its cylinder 18, compressing the fluid 27, and squeezing the rubber cup 25 around the head and neck of the bottle 12, causing the cap or closure 11 to conform with the ridges of the neck of the bottle and, at the same time, forcing the cork 41 firmly in place. This results in a uniformly squeezed and crimped cap, giving an hermetic seal and a tamper-proof closure for the bottle.

Compressed air is then released from the top

end of the cylinder 13 and introduced into the bottom end thereof below the piston 14. The first action is to raise piston 17 until it meets plug 32, because of the helical springs 23, which hold the crimping head 19 against guide rod stops 20. After the piston 17 engages the plug 32, further lifting of the piston 17 raises the head 19 away from stops 20, compressing springs 23, and away from the bottle, clearing the same so that another bottle and cap can be moved into place and the operation repeated.

Figure 2 illustrates a second embodiment of my invention, generally utilizing the principle of the first embodiment. In this case, the fixedly mounted cylinder 18^a and its piston 17^a form a unit with the air cylinder 13^a, having a stroke equivalent to or corresponding with the stroke of the piston 17 of Figure 1. The air cylinder may consist of a thin-walled intermediate hollow steel cylindrical portion closed at its ends by ported upper and lower heads 24^a and 24^b, and be supported at an adjusted height, as in the preceding embodiment. The air piston 14^a has a stroke equivalent to that of the piston 17^a, since the only function of the unit in this case, is to provide the hydraulic pressure.

The lifting of the hydraulic crimping head 19^a from, and its return to, the bottle can be accomplished in many ways, either by a separate mechanical device or by hand. One desirable method is to support this head 19^a by means of a helical spring 23^a above the bottle to be capped, or the bottling line, and to have the operator place the head 19^a over the head and neck of the bottle 12^a, actuating the crimping mechanism as by means of an electric control by closing a circuit, to effect admission of air under pressure above the cylinder 14^a, by pressing a button 42^a, and then remove the head after the crimp is completed and place it over the succeeding bottle, repeating the operation.

The expansion chamber is in this case provided at 29^a and an air relief valve 43 allows air to breathe in and out of the expansion chamber without allowing the water to pass out with it. A "bleed" port 33^a is also provided, so that when the hydraulic piston 17^a is in its upper position, the lower or pressure chamber is connected with the expansion chamber, allowing any trapped air to bleed out as in the first embodiment. The compression chamber of the hydraulic cylinder 18^a is connected to the chamber of this crimping head 19^a by hydraulic hose 44. Except as specifically described, the second embodiment may correspond with the first.

In both of the forms illustrated, the admission and release of air to and from the air cylinder may be electrically controlled in accordance with Figure 3. In said figure, I have shown a port 45 through which air under pressure goes to a valve 46 slidably in a suitably ported chamber 46' and controlling the admission and exhaust of air with respect to said cylinder through ports 47 and 48 respectively in the upper and lower or head and rod ends of said cylinder. Upon closing a switch 49 or 49^a, as by pressing a button such as the bottle-operated button 42 of Fig. 1 or the hand operated button 42^a of Fig. 2, a circuit is established through a battery, or other source of electrical energy 51, through solenoid 52, surrounding armature 53 connected to said slide valve, moving the latter up, against the force of return spring 54, acting between an abutment 55 and a shoulder 56 on the valve rod 57, biasing the valve toward normally lower posi-

tion, to admit pressure to the head end of the cylinder 13 or 13^a, through port 47 or 47^a, and exhaust it from the rod end thereof through port 48 or 48^a. This causes the piston 17 or 17^a, as the case may be, to move down and develop the necessary hydraulic pressure to effect crimping of a cap on the head and neck of the bottle 12 or 12^a. Upon opening the switch 49 or 49^a, the spring 54 moves the valve in the opposite direction, allowing the air to exhaust from the head end of the cylinder 13 or 13^a, through port 47 or 47^a, and be admitted to the rod end through port 48 or 48^a, thereby first releasing the pressure on the deformable foiling head 25 or 25^a and then, in the case of the first embodiment, withdrawing said head 25 from the head and neck of the bottle. In the case of the second embodiment, this withdrawal of the head 25^a may be effected by the operator.

Figure 4 shows an alternative mechanical control for the valve 46, comprising a manually-operable lever 59 pivoted to a fixed support at 60 and to the end of a control rod 61, which is continued to connect with said valve, as illustrated in Fig. 3.

Figure 5 shows another alternative mechanical control for the valve 46, comprising a roller 62 pivoted on a lever 59^a which is, in turn pivoted to a fixed support at 60^a. A cam 63 fixed on shaft 64 which is turned in synchronism with mechanism (not shown) for feeding bottles 12 in place to have caps crimped thereon, serves as an alternative for the operator's hand on the lever 59 of Fig. 4, for operating the roller carrying lever 59^a.

From the foregoing, it will be seen that I have devised an improved machine for crimping caps on the heads and necks of bottles, which machine may be controlled electrically or mechanically. It will also be seen that, in addition to the advantages before enumerated, my machine avoids bottle breakage, even in the form of Fig. 1, by resiliently bringing the crimping head in place over the heads and necks of bottles by limited air pressure, rather than excessive mechanical force. Thus, even if the edge of the crimping head struck the head of a bottle, rather than receiving said head, the bottle would not be broken under normal conditions.

Although preferred embodiments of my invention have been disclosed, it will be understood that modifications may be made.

I claim:

1. In a bottle capping machine, in combination, an hydraulic cylinder, a deformable crimping cup, said cylinder containing a liquid which when subjected to pressure deforms said crimping cup, a piston in said cylinder for placing said liquid under pressure, said cylinder being connected to said crimping cup for applying crimping pressure thereto when receiving the head and neck of a bottle to be capped, a second cylinder in tandem with said first cylinder, a piston located and movable axially in said second cylinder, a rod connecting said pistons so that they move together, and means for introducing compressed air to either side of the piston in said second cylinder, so as to cause it, to either move said hydraulic piston to deform said crimping cup about a received cap on the head and neck of a bottle, or return said hydraulic piston to release the pressure on said cup.

2. In a machine for crimping foil cups over the heads and necks of bottles, in combination, a compressed-air operating cylinder mounted

above a bottle support, an hydraulic capping cylinder of smaller diameter mounted in tandem with said operating cylinder, a deformable crimping cup connected to the lower end of said capping cylinder, a piston in each cylinder, a rod rigidly extending from one piston to the other to cause them to reciprocate in unison, liquid in said capping cylinder beneath its piston, and about said cup, and means for introducing compressed air to said operating cylinder on a selected side of its piston to cause either descent with a downward movement of the capping piston in its cylinder and a deformation of said crimping cup, or an upward return of both to starting position.

3. In a bottle capping machine, in combination, an hydraulic cylinder, a deformable crimping cup, said cylinder containing a liquid which when subjected to pressure deforms said crimping cup, a piston in said cylinder for placing said liquid under pressure, said cylinder for the purpose being connected to said cup for applying crimping pressure thereto when it has received the head and neck of a bottle to be capped, a second cylinder in tandem with said hydraulic cylinder, a piston located and movable axially in said second cylinder, a rod connecting said pistons so that they move together, a slide valve for alternately introducing compressed air to either side of the piston in said second cylinder, and control means for moving said slide valve one way or the other, so as to either introduce air to the outer end of the second cylinder to move the hydraulic piston to deform the crimping cup about a received cap on the head and neck of a properly placed bottle, or introduce it to the inner end of said second cylinder to return said hydraulic piston to release position.

4. In a machine for crimping foil caps over the heads and necks of bottles, in combination, a compressed air operating cylinder mounted above a bottle support, an hydraulic capping cylinder of smaller diameter, mounted in tandem with said operating cylinder, a piston in each cylinder, a rod rigidly extending from one piston to the other to cause them to reciprocate in unison, liquid in said capping cylinder beneath its piston, a deformable crimping cup connected to the lower end of said capping cylinder, an expansion chamber disposed above and connected to said hydraulic cylinder, said expansion chamber being closed by means allowing air to escape but trapping entrained liquid, and a bleed port extended from a position in said hydraulic cylinder below the upper position of its piston to at every stroke allow liquid to flow from said expansion chamber back into said cylinder, below the piston, a deformable crimping cup connected with the lower end of said capping cylinder, and means for introducing compressed air to said operating cylinder on a selected side of its piston to cause either descent with a downward movement of the capping piston in its cylinder and a deformation of said crimping cup, or an upward return of both to starting position.

5. In a machine for crimping foil caps over the heads and necks of bottles, an air cylinder, a piston therein, an hydraulic cylinder, a piston therein, an expansion chamber disposed above and connected to said hydraulic cylinder and a bleed port extended from a position in said hydraulic cylinder below the upper position of its piston to at every stroke allow liquid to flow from said expansion chamber back into said cylinder, below the piston, a rod connecting both pistons

so that they act together, a crimping cup in said hydraulic cylinder, and means allowing movement of said cylinders with respect to one another, whereby only a portion of the stroke of the air cylinder is utilized to move the cylinders with respect to one another and the remainder of the stroke utilized to actuate the piston in the hydraulic cylinder to stress the cup to a controlled extent only.

6. In a foil capping machine a capping cylinder, a deformable crimping cup connected to the mouth of said cylinder, an hydraulic piston in said cylinder, an expansion chamber disposed above and connected to said hydraulic cylinder and a bleed port extended from a position in said hydraulic cylinder below the upper position of its piston to at every stroke allow liquid to flow from said expansion chamber back into said cylinder, below the piston, and means for moving said piston only enough to provide positive crimping of a cap on a bottle head and neck, by limiting compression so that the cup will not be ruptured if a bottle is not in place.

7. In a bottle-capping machine, in combination, an hydraulic cylinder, a deformable crimping cup connected to the lower end of said cylinder, said cylinder containing a liquid which when subjected to pressure deforms said crimping cup, an hydraulic piston located and movable axially in said cylinder, said cylinder being mounted for axial movement in a predetermined path to and from operative position with respect to a bottle to be capped, a second cylinder, guide rods extending longitudinally therefrom and carrying stops adjacent their outer ends, said capping cylinder being reciprocably mounted on said rods, between a position adjacent said second cylinder and said stops, where said capping cylinder is in operative position with respect to a bottle to be capped, resilient means urging said cylinders apart, a piston located and movable axially in said second cylinder, a rod connecting said pistons so that they move together, and means for introducing compressed air to either side of the piston in said second cylinder, so as to cause it to either move from the outer end of its cylinder to, assisted by said resilient means, first move said hydraulic cylinder and its piston to operative position in engagement with said stops, and then move said hydraulic piston in its cylinder to deform said crimping cup about a received cap on the head and neck of a properly placed bottle, or move from the inner end of its cylinder to first return the hydraulic piston to release the crimping cup, and then recompress the resilient means and return the hydraulic cylinder to a position adjacent said second cylinder.

8. In a machine for crimping foil caps over the heads and necks of bottles, in combination, a compressed-air operating cylinder mounted above a bottle support, guide rods extending down from said cylinder and terminating in stops, an hydraulic capping cylinder of smaller diameter reciprocably mounted on said guide rods for movement from said operating cylinder to said stops and return, a deformable crimping

cup connected to the lower end of said capping cylinder, said stops being positioned at a height above said bottle support so that, when engaged by said capping cylinder, the crimping head is at a height operative for receiving the head and neck of a bottle on said support therebeneath a coil spring on each rod urging said capping cylinder into engagement with said stops, a piston in each cylinder, a rod rigidly extending from one piston to the other to cause them to reciprocate in unison, liquid in said capping cylinder beneath its piston, and means for introducing compressed air to said operating cylinder on a selected side of its piston to cause either descent with, first, a simultaneous spring-assisted movement of the capping cylinder and its piston, until the former engages said stops, and then a downward movement of the capping piston in its cylinder and a deformation of said crimping cup, or an upward return of first the capping piston in its cylinder, and then both to starting position with a compression of said springs.

9. In a bottle-capping machine, in combination, an hydraulic cylinder, a crimping head, a deformable crimping cup mounted therein and connected by a flexible hose to receive pressure developed in said cylinder, means resiliently suspending said head, said cylinder containing a liquid which when subjected to pressure thus deforms said crimping cup, a piston located and movable axially in said cylinder, a second cylinder in tandem with said first cylinder, a piston located and movable axially in said second cylinder, a rod connecting said pistons so that they move together, and means for introducing compressed air to either side of the piston in said second cylinder, so as to cause it, when moving from the outer end of its cylinder, to move said hydraulic piston, to deform said crimping head about a received cap on the head and neck of a bottle over which said crimping head may be placed.

10. In a machine for crimping foil caps over the heads and necks of bottles, a compressed air operating cylinder disposed above a bottle support, an hydraulic cylinder of smaller diameter, a crimping head and enclosed deformable cup resiliently suspended therebeneath for movement with respect to said cylinder, for receiving the head and neck of a bottle therebeneath, a piston in each cylinder, a rod rigidly extending from one piston to the other to cause them to reciprocate in unison, a flexible hose connecting said crimping head and hydraulic cylinder, liquid in said head, hose and hydraulic cylinder beneath its piston, and means for introducing compressed air to said operating cylinder on a selected side of its piston to cause either descent with a simultaneous movement of the hydraulic piston and crimping cup, or a return of both to starting position.
